MACHINE FOR SLOTTING KEY BLANKS

Sam Reisner, Pacific Palisades, Calif., assignor to Osco
Corporation, a corporation of California

Filed Oct. 23, 1967, Ser. No. 9,113

Term of patent 14 years

U.S. Cl. D55—1
Int. Cl. D15—05

Fig. 1.

FIG. 2.

FIG. 3.

FIG. 4.

FIG. 5.

FIGURE 1 is a front elevational view of a machine for slotting key blanks showing my new design;

FIGURE 2 is a side elevation as seen from the right of FIGURE 1;

FIGURE 3 is a top plan view thereof;

FIGURE 4 is a side elevation as seen from the left of FIGURE 1; and

FIGURE 5 is a rear elevation.

I claim:

The ornamental design for a machine for slotting key blanks, substantially as shown.
